DESIGN FOR A SCALPEL

Reinhardt H. Brown, Fremont, Ohio

Application January 10, 1936, Serial No. 60,519

Term of patent 7 years

To all whom it may concern:

Be it known that I, Reinhardt H. Brown, a citizen of the United States, residing in the city of Fremont, county of Sandusky, and State of Ohio, have invented a new, original, and ornamental Design for a Scalpel, of which the following is a specification, reference being had to the accompanying drawing, forming part thereof.

In the drawing, Figure 1 is a side elevational view of the scalpel showing my new design; Figure 2 is a top plan view of the scalpel.

My design is characterized by the configuration of the scalpel handle wherein the walls and upper edge are transversely grooved or serrated in conjunction with the tapering beveled upper and lower edges.

I claim:

The ornamental design for a scalpel as shown and described.

In testimony whereof, I affix my signature, this 8 day of January, 1936.

REINHARDT H. BROWN.
